UNITED STATES PATENT OFFICE.

RALPH HINCHLIFFE, OF ROCKFORD, ILLINOIS, ASSIGNOR TO BURSON KNITTING COMPANY, OF ROCKFORD, ILLINOIS, A CORPORATION OF ILLINOIS.

KNITTED STOCKING.

Application filed September 28, 1922. Serial No. 591,088.

To all whom it may concern:

Be it known that I, RALPH HINCHLIFFE, a citizen of the United States, residing at Rockford, in the county of Winnebago and 5 State of Illinois, have invented certain new and useful Improvements in Knitted Stockings, of which the following is a specification.

This invention pertains in general to knitting and more particularly to knitted stockings, and while it should not be understood as being exclusively confined to knitted stockings of the seamless fashioned type, it is so illustrated herein.

15 The primary purpose of my present invention is to provide a stocking of novel structure and appearance, which will possess the requisite elasticity, be durable in character and present a striking, novel and pleasing appearance.

Other objects of the invention will be readily appreciated as the same becomes better understood by reference to the following description when considered in connection 20 with the accompanying drawings.

Referring to the drawings:

Fig. 1 is a side elevation of a stocking embodying my invention; and

Fig. 2 is a fragmentary enlarged view 30 showing the arrangement of the stitches in the stocking.

Referring to the drawings, the leg portion of the stocking, designated generally by reference character 3 and also the foot and 35 top portions, if desired, is knit so as to provide draw stitches on the outer face of the stocking which impart to the stocking a distinctive and pleasing appearance.

While any desired number of different 40 colored yarns may be employed in the formation of the stocking, I have shown in Fig. 2 for illustrative purposes, two colors of yarns, namely, white yarns 4 and colored yarns 5. The number of different colors 45 employed, however, may be varied to produce desired effects without departing from the essence of the invention.

In the knitting of the stocking, certain 50 wales are composed of plain stitches, while others comprise draw stitches. The relative number of plain and draw stitch wales and

their relative arrangement may be varied as desired, but for illustrative purposes I have shown in Fig. 2 a stocking in which the plain stitch wales 6 alternate with draw 55 stitch wales 7. The draw stitches 8 of the various wales are preferably alternated in each wale with plain stitches 9, and by staggering the draw stitches in adjacent draw stitch wales a unique and pleasing appearance is 60 imparted to the stocking.

The stocking possesses, as the result of its novel construction, the requisite elasticity and is strong and durable, as well as novel in appearance, and it is capable of being 65 manufactured rapidly and economically on a flat bed machine which is adapted to produce seamless fashioned stockings.

While I have illustrated and described a preferred embodiment of the invention, it 70 should be manifest that the arrangement of the stitches may be varied to produce a wide variety of patterns without departing from the essence of the invention as set forth in the following claims.

I claim:

1. A knitted stocking comprising wales of plain stitches disposed in alternation with wales of alternate plain and draw stitches, said knitting being done with two yarns of 80 different colors in such order that the two yarns appear in alternation on the face of the fabric in the plain stitch wales and one yarn appears continuously in wales of alternate plain and draw stitches.

2. A knitted fabric composed of two yarns of different colors knit in wales of plain stitches disposed in alternation with wales of alternate plain and draw stitches, each 85 yarn being knit in successive courses alternating with like courses of the other yarn.

3. A knitted fabric composed of two yarns of different colors knit in wales including draw stitches alternated with plain stitches and flanked on either side by plain stitch 90 wales, said yarns being each knit in alternate courses so that both appear on the face of the fabric in the plain stitch wales and one yarn only appears on the face of the fabric in wales of alternate plain and draw 100 stitches.

RALPH HINCHLIFFE.
